The ornamental design for a novelty stethoscope attachment kit, as shown and described.

DESCRIPTION

FIG. 1 is an environmental front view of a first embodiment of a novelty stethoscope attachment kit showing my new design;

FIG. 2 is an environmental rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is an environmental front view of a second embodiment thereof;

FIG. 8 is an environmental rear elevational view thereof;

FIG. 9 is a top plan view thereof;

FIG. 10 is a bottom plan view thereof;

FIG. 11 is a right side elevational view thereof;

FIG. 12 is a left side elevational view thereof;

FIG. 13 is an environmental front view of a third embodiment thereof;

FIG. 14 is an environmental rear elevational view thereof;

FIG. 15 is a top plan view thereof;

FIG. 16 is a bottom plan view thereof;

FIG. 17 is a right side elevational view thereof; and,

FIG. 18 is a left side elevational view thereof.

The broken line showing of the stethoscope in FIGS. 1, 2, 7, 8, 13 and 14 is for illustrative purposes only, merely showing the kinds of stethoscopes that may be used with the instant invention, and forms no part of the claimed design.
